CENTRIFUGAL MACHINE

George Aitken, Rutherglen, Scotland, assignor to
 Watson Laidlaw & Company Limited, Glasgow,
 Scotland, a corporation of Great Britain and
 Northern Ireland

Application November 7, 1934, Serial No. 751,939
 In Great Britain September 11, 1934

4 Claims. (Cl. 210—63)

This invention relates to that type of centrifugal machine, principally used for hydroextraction, including a monitor casing for housing the rotary basket and provided with a hinged cover which can be opened only when the basket is at rest.

The present invention has for its primary object the provision of improved means for locking the cover, including a bolt which is prevented from retraction to unlock the cover while the basket is in motion.

A further object is the provision of improved bolt-unlatching means necessitating the use of both hands of an operative.

Cover-locking means constructed in accordance with the invention is illustrated in the accompanying drawings in which Fig. 1 is a vertical section, Fig. 2 a part plan horizontal section, and Fig. 3 a side elevation, the bolt being shown in shot position; Fig. 4 is a part front end elevation, part transverse vertical section; Figs. 5 and 6 are longitudinal vertical sections showing progressive steps in the actuation of the bolt-unlatching means; Fig. 7 is a side elevation of the monitor casing, drawn to a smaller scale.

Referring to the drawings, 1 denotes the rotary basket and 2 the monitor casing, which houses the basket and which is fitted with a hinged cover 3.

Mounted on top of the monitor casing 2 is a horizontally slideable bolt 4 adapted, when shot, to enter a socket or aperture 5 in a keeper bracket 6 attached to the cover 3, whereby to lock the cover 3 in shut position. Pivoted at 7 to a bracket 8 fixed within the monitor casing 2 below the bolt 4 is a two-armed pendulous lever having an upper arm 9 and a lower arm 10. The arm 9 presents a slot 11 straddling a pin 12 fitted to the rear end of the bolt 4. The arm 10 carries a roller 13 engageable by strikers rotating with the basket 1 and constituted, in the construction shown, by enlarged heads 14 of rivets 15 serving to attach to the basket 1 the flange 16 of an annular top wall 16. Cut in the top face of the bolt 4 are ratchet teeth 17 engageable by a latch member 18 pivoted at 19 within a box 20 which accommodates the bolt 4 and which is attached to the monitor casing 2. Slidable in parallel with the bolt 4 and arranged one on each side of the bolt 4 are two cam slides 21, 22 fitted with ears 23, 24, respectively, adapted for engagement by the thumbs of an operative. To unlock the cover 3, the operative, by pushing on the ears 23, 24, displaces the cam slides in the direction indicated by the arrow 25 (Fig. 1) in opposition to the pull of springs 26, 27 acting, respectively, on the cam slides 21, 22. Access to the

ears 23, 24 may be gained only through lateral openings 23', 24', respectively, in a shield 35 covering the box 20, said openings 23', 24' being so dimensioned and located that the operative is compelled to use both hands in order to effect displacement of the cam slides 21, 22. The latch member 18 is provided near its free end with a follower pin 28 the ends of which cooperate, respectively, with cam edges presented by the slides 21, 22. The slide 21 is formed with an inclined cam edge 29 extending between upright edges 30, 31. The slide 22 is formed with an inclined cam edge 32 emerging at its forward end into a depressed notch 33 and at its rear end into a short oppositely inclined edge 34. Unitary with the slides 21, 22 are projecting tongues 21', 22', respectively.

When the lever arm 10 is positioned with the roller 13 resting on the outer peripheral wall of the basket 1, as shown in dotted lines in Fig. 1, the basket 1 being stationary, the bolt 4 is retracted, permitting the cover 3 to be opened. In the retracted position of the bolt 4, as shown in Fig. 6, the teeth 17 are disposed rearwardly of the latch member 18 which rests on the untoothed forward portion of the bolt 4. When rotation of the basket 1 is initiated, the lever arm 10 is impelled outwardly and upwardly into the position shown in full lines in Fig. 1, by the impact of one or more of the strikers 14 with the roller 13, whereby the bolt 4 is shot, as shown in Fig. 1, and the cover 3 locked. In the forward or shooting travel of the bolt 4 the latch member 18 drops by gravity into locking engagement with one or other of the teeth 17 and thereby retains the bolt 4 in shot position. When the latch member 18 drops into locking engagement with the bolt 4, one end of the pin 28 enters the notch 33 in the slide 22, and the other end of the pin 28 engages the low end of the cam edge 29 of the slide 21. Rotation of the basket 1 being arrested, in order to unlock the cover 3, the operative pushes on the ear 23 with the thumb of one hand and on the ear 24 with the thumb of his other hand. As one end of the pin 28 is in engagement with the notch 33 in the slide 22, the slide 22 is immovable until the pin 28 is withdrawn from the notch 33. On forward displacement of the slide 21 to the position shown in Fig. 5, the cam edge 29, acting on the pin 28, raises the latch member 18 until the pin 28 vacates the notch 33, the movement of the latch member 18 being insufficient to release the bolt 4. While maintaining pressure on the ear 23 to hold the slide 21 at the forward

end of its travel, the operative, by pushing on the ear 24, displaces the slide 22 forwardly, as shown in Fig. 6, in opposition to the spring 27, whereby the cam edge 32 engages the pin 28 and disengages the latch member 18 from the bolt 4, which latter is thereupon retracted under the action of gravity on the lever 9, 10, the arm 10 swinging downwardly and inwardly to initial position. In the forward positions of the slides 21, 22 the tongues 21', 22' enter the aperture 5 in the keeper bracket 6 and prevent the cover 3 from being opened until both cam slides 21, 22 are permitted to return to initial position under the action of the springs 26, 27, on release by the operative of the ears 23, 24.

Should the basket 1 be rotating when the operative seeks to actuate the slides 21, 22 to disengage the latch member 18, the lever 9, 10 will normally vibrate once only and will be held by the latch 18 against further vibration. If the operative maintains the slide 22 in forward position while the basket 1 is rotating, the latch member 18 will, by virtue of the provision of the cam edge 34, re-engage the bolt 4 and hold it in shot position.

I claim:—

1. A centrifugal machine embodying, in combination with a rotary basket and a monitor casing having an openable cover, a cover-locking

bolt, a lever mounted on said monitor casing for operating said bolt, striking means rotatable with the basket and engageable with said lever to effect the shooting movement of said bolt, latch means for holding said bolt in shot position, and manually operable bolt-unlatching means mounted on said monitor casing to permit withdrawal of said bolt by said lever until the next engagement of said lever by said striking means.

2. A centrifugal machine as claimed in claim 1 in which the bolt-unlatching means comprises a pair of slides having cam edges engageable with the latch means to effect the unlatching of said bolt.

3. A centrifugal machine as claimed in claim 1 in which the latch means comprises a pivoted latch member engageable with a toothed part of the bolt and the bolt-unlatching means comprises a pair of slides having cam edges and a follower on the latch member with which said cam edges are engageable to effect unlatching of the bolt.

4. A centrifugal machine as claimed in claim 1 in which the lever is constituted as a double-armed lever a depending arm of which carries a follower engageable by the striking means and the other arm of which is operatively connected to the bolt.

GEORGE AITKEN.
